PRODUCTION OF MONOHALOCYCLO-
ALKANES

Louis Schmerling, Riverside, Ill., assignor to Universal Oil Products Company, Chicago, Ill., a corporation of Delaware

No Drawing. Application March 29, 1944,
Serial No. 528,628

12 Claims. (Cl. 260—648)

1

This invention relates to the production of a halonaphthenic hydrocarbon by reaction of a naphthenic hydrocarbon with a halo-olefin. More specifically, the process is concerned with the condensation of a cycloparaffinic hydrocarbon and a halo-olefin in the presence of a metal halide catalyst.

An object of this invention is the production of a halonaphthenic hydrocarbon, which may also be termed a halocycloalkane, by reacting a naphthenic hydrocarbon and a halo-olefin in the presence of a metal halide catalyst.

Another object of this invention is the production of a monohalocycloalkane by the condensation of a cycloparaffin and a monohalo-olefin in the presence of a catalyst of the Friedel-Crafts type.

A further object of this invention is the production of a monohalo-monocycloalkane by condensing a monocyclic-cycloalkane and a monohalo-olefin, the halogen of which has an atomic weight of from about 35 to about 80, in the presence of a Friedel-Crafts type metal halide.

A still further object of this invention is the production of a monochloro-monocycloalkane by condensing a monocyclic-cycloalkane and a monochloro-olefin in the presence of a catalyst of the Friedel-Crafts type.

One specific embodiment of the present invention comprises a process for producing a monohalocycloalkane which comprises condensing a cycloparaffinic hydrocarbon and a monohalo-olefin in the presence of a catalyst of the Friedel-Crafts type.

In this specification and in the claims, the term "naphthenic hydrocarbon" is used to include the saturated monocyclic hydrocarbons having the general formula C_nH_{2n} , as well as bicyclic and polycyclic saturated compounds. The monocyclic compounds are often referred to as cycloparaffins and alkyl cycloparaffins and are also known as cycloalkanes and alkyl cycloalkanes. The cycloparaffins preferably used in my process are those having 5 and 6 carbon atoms in the ring. The lower cycloparaffins having 3 and 4 carbon atoms in the ring may also be condensed with a halo-olefin although these cycloparaffins are not to be considered on an equivalent basis with the naphthenic hydrocarbons of higher molecular weight which have rings containing 5, 6, or 7 carbon atoms per molecule.

Naphthenic hydrocarbons are available in various gasoline and naphtha fractions or they may be obtained as reaction products from certain hydrocarbon conversion reactions, for ex-

2

ample, the catalytic cyclization of aliphatic hydrocarbons followed by hydrogenation of the resultant aromatic hydrocarbons to naphthenic hydrocarbons. Naphthenic hydrocarbons which are of particular interest as starting materials for the present process include cyclohexane, methylcyclopentane, methylcyclohexane, and other alkyl or polyalkyl cyclohexanes. In general, naphthenic hydrocarbons which contain tertiary carbon atoms are preferred.

Halo-olefins which may be condensed with naphthenic hydrocarbons according to the process of the present invention contain at least one halogen atom and one double bond per molecule. 15 Such halo-olefins comprise halo-ethenes, -propenes, -butenes, -pentenes, and halo-alkenes of higher molecular weights. Vinyl chloride, allyl chloride, methallyl chloride, and the corresponding bromine compounds are representative of 20 suitable halo-olefins. The term halo-olefins is also used herein in reference to other unsaturated compounds of carbon, hydrogen, and halogen containing more than one halogen atom and more than one double bond per molecule; such 25 compounds include cis-1,2-dichloro-ethylene, 1,2-dichloropropene-2, etc. Halo-olefins may be formed in any suitable manner such as by the action of a halogen upon an olefinic hydrocarbon at a temperature at which substitution occurs, 30 this temperature being generally substantially in excess of that at which addition of halogen to the olefinic double bond is the principal reaction. Mono-halo-olefins may also be prepared by the removal of one molecule of hydrogen halide from 35 a dihaloalkane by any of several well known methods.

Catalysts of the Friedel-Crafts type utilizable in effecting the interaction of a halo-olefin with a cyclo-paraffin include metal chlorides and 40 bromides and particularly chlorides of aluminum and zirconium. Of these catalytic materials, aluminum chloride is generally more widely applicable in that it possesses substantial catalytic activity at relatively low temperatures.

45 Metal halides of the Friedel-Crafts type are employed as catalysts preferably at temperatures between about -30° and about $+25^{\circ}$ C., although higher temperatures, generally not in excess of about 100° C., are also sometimes utilizable with 50 certain reaction mixtures comprising essentially cycloparaffins and halo-olefins.

Metal halide catalysts of the Friedel-Crafts type may be employed as such, as mixtures, or supported by carriers such as alumina, diatomaceous earth, clay, pumice, activated charcoal,

etc. The materials so utilizable as carriers should have substantially no harmful effect on the catalyst activity of the metal halide or mixture of metal halides employed. In some cases, the catalyst may be dissolved in a suitable solvent such as a nitroparaffin.

While the reaction of a cycloparaffin with a halo-olefin is not understood completely, it is believed that it involves the addition of a cycloparaffin to the double bond of the halo-olefin particularly at temperatures below about 0° C. Such an addition reaction apparently results in the formation of a cycloalkyl halide of higher boiling point than the reactants and with a molecular weight which is equal to the sum of the molecular weights of the reacting cycloparaffin and unsaturated halide. At a higher reaction temperature it appears that a cycloalkyl halide is first formed and then this compound undergoes an intramolecular change or hydrogen disproportionation with the charged cycloparaffin producing a higher boiling cycloparaffin and liberating hydrogen halide. In order to obtain high yields of cycloalkyl halides a molar excess of cycloparaffin to halo-olefin should be present throughout the entire reaction. Generally not more than about 20 molecular proportions of cycloparaffin per molecular proportion of halo-olefins are present in the reaction mixture charged to the process.

The condensation of a cycloparaffin with a halo-olefin, unsaturated halide, or alkenyl halide of the type of vinyl-, allyl-, methallyl-chloride or -bromide, etc., is carried out using either batch or continuous operation. Thus, in batch type operation a halo-olefin is added gradually to a reactor containing a cycloparaffin and a catalyst of the Friedel-Crafts type. The reaction temperature is maintained below about 100° C. but preferably between about -30° and about 25° C. and under sufficient pressure to keep in liquid state a substantial proportion of the reactants. The reaction mixture is also agitated by stirring, shaking, or some other suitable means to effect intimate contact of the reactants and catalyst. During this treatment, the cycloparaffin combines chemically with the halo-olefin to produce a cycloalkyl halide with a molecular weight which is equal to the sum of the molecular weights of the reacting cycloparaffin and halo-olefin. At higher temperatures, some of the cycloalkyl halide may be converted into an alkyl cycloparaffinic hydrocarbon of gasoline boiling range, said hydrocarbons being the principal product of the process when the condensation reaction is carried out at a temperature above about 25° C. in the presence of a catalyst of relatively high activity. At the higher reaction temperatures, hydrogen halide is generally evolved from the reaction mixture. After such a batch type operation, the normally liquid products are separated from the catalyst and the latter is returned to further use in the condensation reaction zone. Hydrogen halide present in the reaction products may be returned to the process or utilized for some other purpose as desired. In some cases it is desirable to commingle hydrogen with the reaction mixture since it has a tendency to increase the active life of the catalyst.

Continuous condensation of cycloparaffin with a halo-olefin is carried out by introducing the halo-olefin, also referred to as an unsaturated halide, or a mixture of a cycloparaffin and said halide to a circulating commingled mixture of a cycloparaffin and a metal halide catalyst, particularly aluminum chloride or another compound

of the Friedel-Crafts type. The mixture of cycloparaffin, halo-olefin, catalyst, and sometimes hydrogen or a hydrogen halide is directed through a mixer or through a reactor containing packing material to effect intimate contact of the catalyst with the reacting hydrocarbons. The conditions of temperature and pressure employed in such a condensation treatment are within the limits indicated above, but particular conditions used in any given condensation reaction vary with the molecular weights and reactivities of the reactants, the concentration and activity of the catalyst employed, and other factors.

The following example is given to illustrate the character of the results obtained by the use of the present process, although the data presented are not introduced with the intention of unduly restricting the generally broad scope of the invention.

20 250 parts by weight of methylcyclohexane, 79 parts by weight of allyl chloride, and 20 parts by weight of aluminum chloride were contacted at -15° C. for two hours in a glass-lined reactor equipped with a motor driven stirrer. The reaction product consisted of 303 parts by weight of liquid and 46 parts by weight of a red, viscous catalyst layer. The liquid product was then washed, dried, and distilled. Besides unconverted methylcyclohexane, this liquid product contained 12% by volume of liquid material boiling between 225° and 253° C. consisting of isomeric chloropropylmethylcyclohexanes with a refractive index, n_{D}^{20} , of from 1.4680 to 1.4819 and a density of from 0.93 to 0.98. The reaction product also contained about 3% by volume of liquid products boiling between 160° and 175° C. and comprising essentially propylmethylcyclohexane, or an isomer thereof formed by intramolecular hydrogen-hydrogen chloride transfer between methylcyclohexane and chloropropylmethylcyclohexane.

Another run in which 100 parts by weight of methylcyclohexane, 50 parts by weight of allyl chloride and 10 parts by weight of aluminum chloride were reacted at 20° C. yielded 12 parts by weight of a condensation product boiling chiefly at 70-75° C. at a pressure of 3.5 mm. of mercury and comprising essentially chloropropylmethyl cyclohexanes and isomers thereof with a refractive index, n_{D}^{20} , of from 1.4620 to 1.4660. Analysis of the material showed that it contained 69.4% carbon and 10.6% hydrogen. The values calculated for a compound having the formula $C_{10}H_{19}Cl$ are 68.9% carbon and 11.0% hydrogen. In this run there was also obtained 6 parts by weight of propylmethylcyclohexane or its isomers.

The novelty and utility of the process of the present invention are evident from the preceding specification and examples, although neither section is intended to unduly limit its generally broad scope.

I claim as my invention:

1. A process which comprises reacting a naphthenic hydrocarbon with a halo-olefin in the presence of a Friedel-Crafts metal halide catalyst at a temperature of from about -30° C. to about 25° C.

2. A process which comprises reacting a cycloparaffinic hydrocarbon with a halo-olefin in the presence of a Friedel-Crafts metal halide catalyst at a temperature of from about -30° C. to about 25° C.

3. A process which comprises reacting a cycloparaffinic hydrocarbon with a halo-olefin in the presence of a Friedel-Crafts metal halide catalyst at a temperature of from about -30° C. to about

25° C. under sufficient pressure to keep in liquid state a substantial proportion of the reaction mixture.

4. A process which comprises reacting a cyclo-paraffinic hydrocarbon with a chloro-olefin in the presence of a Friedel-Crafts metal halide catalyst at a temperature of from about -30° C. to about 25° C.

5. A process which comprises reacting a cyclo-paraffinic hydrocarbon with a bromo-olefin in the presence of a Friedel-Crafts metal halide catalyst at a temperature of from about -30° C. to about 25° C.

6. A process which comprises reacting an alkyl cyclopentane hydrocarbon with a chloro-olefin in the presence of a Friedel-Crafts metal halide catalyst at a temperature of from about -30° C. to about 25° C.

7. A process which comprises reacting an alkyl cyclohexane hydrocarbon with a chloro-olefin in the presence of a Friedel-Crafts metal halide catalyst at a temperature of from about -30° C. to about 25° C.

8. A process which comprises reacting an alkyl cyclohexane hydrocarbon and a chloro-olefin in the presence of an aluminum chloride catalyst at a temperature of from about -30° C. to about 25° C.

20

25

9. A process which comprises reacting an alkyl cyclohexane hydrocarbon and a monochloro-olefin in the presence of an aluminum chloride catalyst at a temperature of from about -30° C. to about 25° C.

10. A process which comprises reacting methyl cyclohexane and a chloro-olefin in the presence of an aluminum chloride catalyst at a temperature of from about -30° C. to about 25° C.

11. A process which comprises reacting methyl cyclohexane and a monochloro-olefin in the presence of an aluminum chloride catalyst at a temperature of from about -30° to about 25° C.

12. A process which comprises reacting methyl cyclohexane and allyl chloride in the presence of an aluminum chloride catalyst at a temperature of from about -30° C. to about +25° C.
